Patented Oct. 17, 1922.

INVENTOR
A. R. TURNER
By John Michael Aley

UNITED STATES PATENT OFFICE.

ALBERT RICHARD TURNER, OF BRIGHTON, ENGLAND.

PHOTOGRAPHIC FILM-DEVELOPING APPARATUS.

Application filed September 27, 1919. Serial No. 327,002.

To all whom it may concern:

Be it known that I, ALBERT RICHARD TURNER, a subject of the King of Great Britain and Ireland, and a resident of 5 Brighton, England, have invented a certain new and useful Improvement in Photographic Film-Developing Apparatus, of which the following is a specification.

This invention has reference to photographic film developing apparatus for daylight and other working and consists in an improved construction and arrangement introducing a novel mode of unwinding the film off the spool inside the developing tank, 15 viz:—by rotation of the lid on the tank. Other features of the invention will be apparent from the following description.

A practical embodiment of the said invention is illustrated by the accompanying 20 sheet of drawings, wherein:—

Figure 1 is a top plan view of the tank with the lid removed.

Figure 2 is a vertical sectional view of the tank showing the lid in position.

25 Figure 3 is a view of one form of clamp means hereinafter described.

Figure 4 is a detail view of a film spool carrier.

The developing tank proper *b* is furnished 30 with means for holding one end of the film, which is unwound by rotation of the lid of the tank, this action constituting an essential feature of the invention. That is to say the present invention contemplates the 35 provision of a developing tank having a lid *g* rotatable thereon and carrying eccentrically therewith a film roll engaging device for conveying the film through the solution in the developing tank over a spiral course 40 or path when the lid is rotated on the tank.

In the embodiment now being described, the tank *b* is fitted with a removable spiral film guide member *e* which forms a guide way for the film roll. The developed length 45 of the spiral *e* is slightly longer than the longest film to be dealt with by the apparatus. In practice the inner end *e*² of the spiral *e* is provided with a hook portion *e*³ having the recess *e*⁴ which receives the bent 50 end of the film when the latter is placed in the guideway *e*. A preferable manner of detachably fitting the spiral in position is by means of a sliding fit of the vertical edge at *e*¹ in the slideway *f* secured to the inner 55 side wall of the tank *b*.

The lid *g* is furnished with a handle *h*

pivoted at *h*², having if desired an exterior knob *h*³ and an inwardly extending crank arm *h*⁴. In one form the handle *h* may be tubular and the member *h*³ a pneumatic bulb, 60 so that by squeezing said pneumatic bulb the contents of the developing tank will be agitated through the hollow member *h* and arm *h*⁴ which extends into the tank.

In operation, the film spool is first fitted 65 with a film-spool carrier, one type of which is shown in Figure 5. Here is seen a body portion *i* with inturned fingers *i*¹ which are shaped to grip the spool extremities, either by means of pivots *i*² to fit in the bore formed 70 in the end of some spools, or by equivalent means to take over spindle ends projecting from some film spools. The body portion *i* carries a tubular portion *i*³ which is adapted to receive the arm *h*⁴ of the pivoted handle 75 *h* of the lid member.

When the spool is fitted with such a carrier, the excess paper wrapping of the film is removed and the film end bent back so that it extends into recess *e*⁴ when the spool 80 is dropped into the first turn *e*⁵ of the spiral film guideway *e*. A convex flat or other vertically arranged spring *j* may be secured to the guideway *e* to keep the film from unwinding (when the spool is of small diameter and loosely fits the space *e*⁵) before the lid is in position. The film end is clamped in recess *e*⁴ by any convenient means, such, for instance, as that shown in Figure 3. A wedge member *k* moves up 90 and down in a sliding member *k*¹, there being a pin and slot *k*² and *k*³ to hold the two members together. *k*⁴ is a serrated or other gripping edge. This device is dropped into the recess *e*⁴ with the serrated edge *k*⁴ 95 against the film; the clamping is effected by depressing the wedge *k*. A bracing bar *e*⁶ may be fitted to preserve the shape of the spiral guideway extremity. After the spool is inserted in such fashion in the developing tank *b*, the solution is poured in, and the lid *g* is placed on, with the arm *h*⁴ inserted into the sleeve *i*³ of the film-spool carrier. Now, by rotating the lid *g* on the tank *b*, the pivoted handle *h* unwinds the 100 film by carrying the spool around the spiral guideway *e* up to the extremity *e*¹, or such other distance necessary to completely unwind the film.

Separate spool-carriers, one type of which 110 is illustrated in Figure 4 may be supplied to take various sizes and types of spools.

Having now described my invention, what I claim as new and desire to secure by Letters Patent of the United States is:—

1. In a device of the class described, a developing tank, a spiral guide element forming a guide-way in said tank and having a film roll receiving pocket located at the center of the tank, means at the inner end of said guide way for holding the free end of the film, a lid for said tank, and means carried by said lid and adapted to engage with the film roll to pull the same through the guide-way when the lid is rotated on the tank.
- 15 2. A photographic film developing apparatus including a circular developing tank, a spiral guide element within the tank forming a guide-way having a film roll receiving portion located at the center portion of the tank, means at the inner end of said guide-way for holding the free end of the film, a lid for covering said tank, and a crank arm eccentrically pivoted to said lid and having a right angular extension projecting 25 into the tank for engaging with the film roll to pull the same around the guide-way to unwind the film when the lid is rotated on the tank.
- 30 3. A photographic film developing apparatus including a developing tank, a spiral

guide member within the tank forming a film roll guide-way extending from the center of the tank to the periphery thereof and said guide member being formed at its inner end to loosely receive the film roll and 35 means also at the inner end of said guideway for holding the relatively free end of the film, a cover for the tank, and film roll engaging means carried by the said cover eccentrically thereof and having a 40 portion for engaging with the film roll to thereby pull the same through the guide way upon the rotation of the cover.

4. A photographic film developing apparatus including a tank, a spiral guide member within said tank and having its inner end formed to receive a film roll, means for clamping the free end of the film to the inner end of said guide member, a cover for the tank, and a crank element pivoted eccentrically in the cover and having a portion 45 for engaging with the film roll to thereby connect the same with the cover whereby the rotation of the latter on the tank will pull the said film roll over a spiral 50 path determined by said guide member.

In testimony whereof I have affixed my signature hereto this 22nd day of August 1919.

ALBERT RICHARD TURNER.
